United States Patent Office

Des. 230,026

Patented Jan. 22, 1974

230,026

VIDEO MONITOR UNIT

John Davis Sims, Cary, N.C., assignor to International
Business Machines Corporation, Armonk, N.Y.

Filed Aug. 27, 1971, Ser. No. 175,812

Term of patent 14 years

Int. Cl. D14—02, 03
U.S. Cl. D26—5 C

FIG. 1

FIG. 2

FIG. 3

FIG. 4

FIG. 5

FIG. 6

FIG. 1 is a perspective view taken from the front and left side of a video monitor embodying my new design;

FIG. 2 is a perspective view taken from the rear and right side;

FIG. 3 is a front elevational view thereof;

FIG. 4 is a rear elevational view thereof;

FIG. 5 is a left side elevational view thereof;

FIG. 6 is a bottom plan view thereof.

I claim:

The ornamental design for a video monitor unit, as shown and described.
